MOUNTING FOR SLIDING DOORS.

1,120,063.

Specification of Letters Patent.

Patented Dec. 8, 1914.

Application filed October 11, 1913. Serial No. 794,573.

To all whom it may concern:

Be it known that we, GEORGE B. KURTZON and RAYMOND J. FAHLE, citizens of the United States, residing at Chicago, in the county of Cook and State of Illinois, have invented certain new and useful Improvements in Mountings for Sliding Doors, of which the following is a specification.

This invention relates to improvements in mountings for sliding doors of the type commonly known as receding doors such as are used in book cases, show cases and similar constructions.

The especial object of the improvements which form the subject matter of this application is to provide the hardware attachments and mountings for cases and receding doors whereby a door which is pivotally connected at its upper corners may be swung outwardly from its closed position to a horizontal position and then pushed inwardly and supported in its horizontal and open position with the minimum amount of friction between the movable parts, and physical effort on the part of the operator.

A further object of our invention is to provide the necessary hardware to accomplish the above results in a simple, strong and economical form, and to so connect and arrange same relative to the door and the case in which the door is hung as to provide against accidental displacement or the breakage of the parts.

A further object is to provide devices that will remain in proper alinement, thus avoiding the binding of the doors in their slideways in the case.

Having the foregoing and other objects of general utility in view, we have designed the hardware mounting illustrated in a preferred form in the accompanying drawing, in which:—

Figure 1 shows partly in section, and partly in elevation, the upper and forward corner of a show case or similar structure and the upper left hand corner of a door frame and the hardware secured thereto which cooperates with the hardware fixed in the case, the door frame being shown in the position it assumes when the door is closed; Fig. 2 corresponds to the showing of Fig. 1, except that the door is shown in its open position; Fig. 3 is a plan view of the bearings and attached plates which are

secured to the door; Fig. 4 is a plan view of the bearing and attached bracket which is secured to the inner wall of the case in which the door is mounted; Fig. 5 is a detail of a stop which limits the sliding movement of the door in its forward or outward direction.

Referring to the details of the drawing 6 represents one of the side walls, 6^a, the top wall, and 6^b, a front frame member of a show case or book case. 7 represents the left hand side member of a door frame and 7^a the upper cross member of said frame while 7^b designates the glass mounted in said frame. 8 indicates a strip of flat metal bent as at 8^b, and provided with screw holes 8^c. One end of this plate is pivotally connected at 8^a with a short flat strap of metal 9, which is provided with screw holes 9^a by which it is secured with suitable screws to the outer face of the door frame member 7. 7^b The bend 8^b provides an offset or depressed portion of the strap 8 in which there is mounted on pivots 10^a, two rollers 10 equipped with ball bearings 10^b. The strap 8 is secured to a wood bar 11 arranged parallel with the door frame, and as there are two of the straps 8, one at each end of the door, it will be obvious that the wood bar 11 will be held rigidly in such parallel relation.

12 represents an angle bar which is attached to the inner face of the end wall 6 of the case a short distance below the top 6^a by screws 12^a. This bar extends from near the front of the case the entire depth of the latter. It will be understood that there are two of these bars, one at each end of the case.

The bracket plate 13 is provided with screw holes 13^a, and at one end is bent up at right angles to provide the lug 13^b, and at the opposite end is mounted upon an axle 14^b, the roller 14 equipped with the anti-frictional ball bearings 14^a. The bracket 13 is placed over the forward portion of the angle plate 12 so that the upper edge of the bracket is just below the horizontal flange of the angle and the roller 14 extends in front of the angle bar and the tread of the roller is also above the horizontal flange of said angle bar, as clearly shown in Figs. 1 and 2. The plate 15 is bent to provide an offset portion 15^b, and is provided with

screw holes 15^a by which it is attached to the under side of the wood bar 11, so that the offset portion slides under the horizontal flange of the angle bar 12, and is adapted to 5 abut against the lug 13^b when the door is drawn forward the full limit necessary to effect its movement to a vertical position.

It will be understood that there will be a plate 15 at each end of the bar 11, and that 10 by reason of the contact of the depressed portion 15^b of said plates they will act as keepers to prevent the derailment of the rollers 10 where the top of the case 6^a is not near enough to said rollers to prevent them 15 from jumping the angel bar 12 which serves as a track.

The front member of the top of the case is grooved as at 6^c to facilitate the turning of the door on its pivotal connection 8^a. 20 When the door is in its closed or vertical position the offset portion 8^b of the plate 8 will rest upon the upper tread of the roller 14, and the inner face of the side member 7 of the door frame will also rest against 25 the periphery of said roller, as shown in Fig. 1, thus holding the door in a vertical plane and also causing it to move rearwardly or inwardly as soon as its lower edge is drawn outwardly, thus causing the door to 30 recede or disappear quickly within the case

and avoiding any jumping or rattling which might otherwise take place.

As shown in the drawings the under side of the case top board 6^a provides the bearing for the rollers 10 in case there should be any 35 upward thrust on said rollers, but it is obvious that some other member or feature of construction might be provided in lieu of the board 6^a in case the door was not mounted in the upper portion of the case or cavity. 40

Having thus described our invention what we claim is:—

In mountings for sliding doors, plates pivotally connected with the door and having rollers mounted thereon, means connecting 45 said plates to maintain them in parallel relation, fixed tracks arranged to have said rollers travel thereon, fixed brackets having rollers mounted thereon, said rollers arranged to support said first named plates 50 and the door secured thereto, and means for limiting the forward movement of said door.

In testimony whereof we affix our signatures in the presence of two witnesses.

GEORGE B. KURTZON.
RAYMOND JOHN FAHLE.
